CLAIM

The ornamental design for a cabinet, as shown and described.

DESCRIPTION

FIG. 1 is a perspective view of a cabinet showing my new design;

FIG. 2 is a front elevational view thereof; and,

FIG. 3 is a left side view thereof, the opposite side being a mirror image of the side shown.

The broken line showing of the hardware located on the drawers and doors, and the ornamentation inside the pediment and directly beneath the pediment is for illustrative purposes only and forms no part of the claimed design.
